UNITED STATES PATENT OFFICE.

EDWARD D. FLINT, OF OAKLAND, CALIFORNIA.

DESIGN FOR A HOOF-PAD.

SPECIFICATION forming part of Design No. 29,825, dated December 20, 1898.

Application filed November 11, 1898. Serial No. 696,180. Term of patent 14 years.

To all whom it may concern:

Be it known that I, EDWARD D. FLINT, a citizen of the United States, residing at Oakland, in the county of Alameda and State of California, have invented and produced a Design 5 for a Hoof-Pad; and I do hereby declare the following to be a full, clear, and exact description of said invention, such as will enable others skilled in the art to which it most 10 nearly appertains to make, use, and practice the same.

In the drawings, Figure 1 is a plan view of this design from underneath. Fig. 2 is a rear elevation of the same. Fig. 3 is a cross-section 15 on the line X X.

As disclosed in the drawings, the principal features of my design are the conformation and configuration of the raised portion A' of the friction-pad A. The outline of the portion A' is designed to hug the heels of the 20 horseshoe and converge to a point in the center of the hoof by sweeping curves, the point of junction being truncated by a curve struck from this junction and extending backward

about one-third the distance to the heel. Into 25 the surface thus left elevated are sunk the following configurations: Centrally located, the intaglio B, representing a horseshoe surrounded by the depressions B'. Intersecting in various directions are the shallow channels B². Into the opposite side of the portion A', above referred to, is formed the depression D, extending with an increasing depth 30 from approximately the center of the part X to the heel. The part X is formed with a 35 gradual increase of thickness from the "toe" to the "heel."

Having thus described my invention, what I claim as new is—

The design for a hoof-pad, as herein shown 40 and described.

In testimony whereof I have hereunto set my hand this 13th day of October, 1898.

EDWARD D. FLINT.
